AMBULATORY AIRFIELD CONTROL TOWER

Wilson C. Shepheard, 3040 Broad Creek Road,
Norfolk, Va.

Filed Dec. 27, 1965, Ser. No. 324

Term of patent 14 years

(Cl. D14—3)

FIG.1

FIG.2

FIG. 1 is a perspective view of the front and one side of the ambulatory airfield control tower; and

FIG. 2 is a perspective view of the rear and the other side of the same.

The dominant features of my design reside in the portions shown in full lines.

I claim:

The ornamental design for an ambulatory airfield control tower, as shown and described.
